[57] CLAIM

The ornamental design for a knit baby's bootie, as shown and described.

DESCRIPTION

FIG. 1 is a left side elevational view of a knit baby's bootie, showing my new design, the right side view being a mirror image thereof;

FIG. 2 is a front elevational view thereof;

FIG. 3 is a top plan view thereof; and

FIG. 4 is a rear elevational view thereof.

The bottom plan view is flat and unornamented.
